HERMAN ARVENE GEORGE, OF SUPERIOR, WISCONSIN.

OPTICAL LENS GRINDING AND SURFACING MACHINE.

Application filed April 24, 1923. Serial No. 634,379.

My invention relates to improvements in grinding and surfacing machines and it consists in the constructions, combinations and mode of operation herein described and 5 claimed.

An object of the invention is to provide a machine for grinding and surfacing both spherical and cylindrical optical lenses, the motions through which the machine goes in 10 producing these types of lenses being automatic after proper settings are once made.

Other objects and advantages will appear in the following specification, reference being had to the accompanying drawings, 15 in which:—

Fig. 1 is a perspective view illustrating the general arrangement of the machine,

Fig. 2 is a front elevation thereof,

Fig. 3 is a vertical section taken on the 20 line 3—3 of Fig. 1,

Fig. 4 is a vertical section taken on the line 4—4 of Fig. 1,

Fig. 5 is a vertical section on the line 5—5 of Fig. 1,

Fig. 6 is a longitudinal section on the line 25 6—6 of Figure 2,

Fig. 7 is a detail side elevation of the clutch pinion and brake,

Fig. 8 is a detail plan view of parts shown 30 in Fig. 7,

Fig. 9 is a detail plan view of the stationary base with the cover removed, and

Fig. 10 is a detail section on the line 35 10—10 of Fig. 1 showing the eccentric which oscillates the horizontal arm.

In carrying out the invention provision is made of a base 1 which has any suitable arrangement of webs or lugs 2 on the outside by means of which it may be fastened 40 on top of a table 3. The base 1 is hollow, as shown in Fig. 6, and contains bevel gears 4 and 5 by means of which the arbor 6 is driven.

A lid 7 covers the base 1. The base is intended to be filled with a lubricant so that 45 the various gears may work easily. This lubricant will find its way into the standard 8 in which the arbor 6 has bearing. Adjustments of the arbor may be made by 50 means of a screw 9 at the bottom. The adjustments are fixed by nuts 10. The adjustments are vertical, as may be readily seen in Fig. 6, and are for the purpose of tightening or loosening the arbor in the standard 55 when required.

A boss 11 at one side of the standard 8

supports one end of the main drive shaft 12. This shaft carries the gear 5. The other gear 4 is carried by the arbor and by the engagement of the gears the arbor is driven. 60 The upper end of the arbor extends through an opening in the cover 7. It is slotted at 13 to receive the fastening means or key of either the convex tool 14 (Fig. 1) or the concave tool 15. In practice, the grinding 65 tools may be convex, concave, spherical or cylindrical.

These tools are for grinding and finishing optical lenses. They are commonly known as laps in the art. The lap or grinding tool 14 is for the purpose of producing a concave lens having either a spherical or cylindrical surface. The lap 15 produces a concave lens having either a spherical or cylindrical surface. Reverting now to the 70 base 1 it is to be observed that the shaft 12 passes through a bushing 16 which is fastened in the wall 17 of the base. This wall includes a circular disk 18 which is abutted by a corresponding disk 19 of the upright 75 column 20.

The disk 19 is swivelled on the continuation of the bushing 16. The purpose of this arrangement is to permit adjusting the upright column 20 and its carried parts at 80 either side of a vertical plane centered on the longitudinal axis of the shaft 12. These adjustments are fixed by a clamp device 21. This clamp device is nothing more than a hood which keeps the opposed faces of the 85 disks 18 and 19 in contact.

It has flanges 22 (Fig. 6) which aid this purpose. One side of the clamp device is split at 23 (Fig. 1) and when the binding lever 24 is turned down, the disks are 90 clamped together. The binding device is held in place on the disk 18 by means of a screw 25. The reader will readily see that by means of the clamp device the upright column 20 may be held either vertical or at 95 any degree of inclination at one side or the other within the range of the machine.

Mounted on the exposed end of the main drive shaft 12 is a pulley 26 to which the belt 27 of a suitable driving motor is applied. The shaft 12 also carries a bevel pinion 28 (Fig. 6) which meshes with a similar pinion 29 on the lower end of a shaft 30 in the upright column 20. This column has portions 31 in which the shaft is journaled. 100 The shaft is held in position by a bevel gear 32 which is affixed to the upper end. The

hub of the gear rests on the upper end of the column 20 and therefore may be said to provide a thrust bearing.

Upward extensions 33 from the column 20 furnish support for a pin 34 upon which the ears 35 of the horizontal arm 36 are mounted. The arm 36 is adapted to oscillate upon the pin 34 and this oscillation is entirely independent of the particular adjustment 10 in which the column 20 may be fixed. The oscillation of the arm 36 is controlled by an eccentric 37 which has connections 38 and 39 with the horizontal arm. These connections comprise the tube 38 and rod 39 which latter 15 is adapted to telescope within the tube. The tube 38 has a head 40 (Fig. 1) in which the eccentric operates. The rod 39 has a pivotal connection 41 with the horizontal arm 36. A clamping device 42, including the handle 20 43, is adapted to fix the connections 38 and 39 at any desired adjustment.

The eccentric 37 is carried by a shaft 44, mounted in suitable bearings 45 in the hollow base 1 (Figs. 9 and 10) and carries a worm 25 gear 46 which is driven by a worm pinion 47 on a countershaft 48. This countershaft is driven by a worm gear 49 on the main shaft 12, which gear meshes with a similar pinion 50 on the countershaft. The reader will 30 readily see that the rotation of the grinding arbor 6 is accompanied by an oscillation of the horizontal arm 36, but this particular mode of operation is subject to variations.

For example, it is possible to unloosen the 35 clamping device 42 so that no oscillation of the arm 36 occurs. In this instance, the tube 38 will simply rise and fall, due to the operation of the eccentric 37, but no corresponding motion of the rod 39 will occur on account of the loosened connection at the place 40 42. The position in which the oscillation of the arm 36 occurs may be varied by setting the rod 39 in various relative positions in respect to the tube 38. The same clamping 45 means 42 permits adjusting the arm 36 in such a manner that the oscillation will occur either at the right or left side of the longitudinal axis of the machine.

Reverting now to the bevel gear 32 on the 50 upper end of the upright shaft 30, it is to be observed that this gear meshes with a bevel gear 51 on the pin 34, and that this gear in turn meshes with the bevel gear 52 on the lower end of a short shaft 53 which is 55 practically a continuation of the shaft 30. The pinion 51 acts as the driver and the pinion 52 the driven member for the shafts situated thereabove. The upper end of this shaft carries a bevel gear 54 which meshes 60 with a corresponding gear 55 on a horizontal shaft 56 in the arm 36. Gears 57 and 58 transmit the driving motion of the shaft 56 to the sleeve 75 and spindle 59 which spindle reaches down into proximity with the upper 65 exposed end of the grinding arbor 6. The

driving connections between the gears 52 and 58 may be regarded as the spindle train. It is at the place where the spindle 59 and arbor 6 oppose each other that the grinding and surfacing of the lenses takes place. 70

Explanation of how the grinding tools or laps 14 and 15 (Fig. 1) are fitted upon the grinding arbor is made above. The spindle 59 is adapted to carry the blank to be ground. This is done by means of a lens 75 block 60 to which the blank 61 which is to be ground, is cemented.

The lens block 60 has a socket 62 adapted to be occupied by the ball-pointed end 63 of the spindle 59. This end of the spindle 80 has alining pairs of pins 64 and 65 the latter a little higher than the former, adapted to work in corresponding slots 66 in the socket 62. The connection between the spindle 59 and the lens block 60 is entirely loose with 85 the exception of the driving connection which the engagement of the various pins and slots affords. The reader will see at once that this particular mode of connection between the spindle and lens block provides 90 a ball and socket joint which permits the free oscillation of the spindle according to the operation of the machine. Furthermore, it permits the application of even pressure and keeps the lens in proper position 95 throughout its travel across the lap.

Pressure is obtained by means of a spring 67 which is disposed on the spindle 59 between a collar 68 and a presser foot 69. The presser foot is carried by a bolt 70 which is 100 slidable in a sheath or tube 71. The bolt has a handle 72 by means of which it may be moved up and down in the vertical slot 73 of the tube. This slot has a plurality of laterals 74 (Fig. 2) into any one of which 105 the handle 72 may be pocketed in order to quickly and conveniently set the presser foot 69 at any desired position. Obviously, the farther the presser foot is moved downward, the greater will be the tension of the spring 110 67 and the greater will be the pressure of the lens on the surface of the grinding tool.

A sleeve 75 carries the spindle 59. The sleeve has a key 76 which occupies a slot 77 running lengthwise of the spindle. The 115 key and slot connection causes the spindle to rotate with the sleeve but at the same time to permit relative sliding motion on the spindle. A key 78 fastens the gear 58 to the sleeve so that the latter is rotated. A bearing 79 120 assists in stabilizing both the sleeve and spindle. A handle 80, loose on the upper end of the spindle 59 is provided merely to facilitate adjustments of the machine when such are required. A handle 81 (Figs. 1, 3 and 125 5) projecting from the side of the upright column 20, is for the same purpose.

Bearings 82 (Fig. 6) support the horizontal shaft 56. The horizontal arm 36 is constructed somewhat on the order of a trough 130

in which the shaft 56 and the various driving gears are situated. If desired, this trough may be filled with a lubricant which is sufficiently heavy to prevent excessive leakage at the various downward openings at the slot 53 and sleeve 75. A cover 83 closes the top of the horizontal arm.

Provision is made for stopping the rotation of the grinding or lens spindle 59. This provision is operative only in respect to the rotation of the spindle and does not affect the oscillation of the horizontal arm 36 nor the rotation of the grinding arbor 6. It consists of a clutch lever 84 (Figs. 1 and 7) which is adapted to slide the sleeve 85 (Fig. 8) along a rod 86 to move the bevel gear 51 either into or out of mesh with the companion gears 32 and 52 (Fig. 6). In the former instance, the driving of the spindle 59 is accomplished. In the latter instance, the driving spindle remains dormant.

Furthermore, by means of a brake 87, rigid fixing of the driving spindle may be accomplished. This provision is made so that the upright column 20 may be adjusted in either direction from its vertical position, without changing the relative position or alinement of the lower pin 64 in the spindle 59 to the slot 13 in the grinding arbor. The application of the brake occurs when the lever 84 is moved over far enough to bring the notch 90 into position to fit upon or receive a pin 93 on the adjacent side of the upper part of the column 20.

This notch is one of three formed in the under edge of the lever 84, the others being designated 91 and 92. In placing the lever 84 so as to engage the middle notch 91 with the pin 93, both clutch gear 51 and brake 87 are disengaged and are then in a neutral position. By bringing the notch 92 in engagement with the pin 93, the clutch gear 51 is caused to engage the companion gears 32 and 52 so that driving motion may be imparted. A fork 88 engages an adjacent part of the arm 36 and furnishes a guide for the proper movement of the brake 87. This brake is part of a collar 89 which is perfectly loose on the pin 34. The same is obviously true of the clutch gear 51, i. e. it is perfectly loose on the pin 34, merely being in the nature of an idler.

The lever 84 is pivoted at 94 to the sleeve 85 (Fig. 8). Mention should have been made of the fact that the upper part of the column 20 is encased as shown in Fig. 1, as it would be undesirable to have the driving gears within exposed. The encasement permits filling the chamber formed thereby with a lubricant, which could otherwise not be so readily applied.

The operation may be briefly reviewed to advantage. Driving power is applied at the pulley 26 on the main drive shaft 12, and when thus driven, the shaft 12 in turn ro-

tates the grinding arbor 6 and the lens spindle 59. These parts are driven in the same direction, as the reader can readily ascertain by tracing the driving motion through the various bevel gears. Both the spindle 59 and the arbor 6 are driven at the same rate of speed.

The reader may question how any grinding motion is performed when the arbor and lens spindle turn together. The grinding motion occurs by virtue of the operation of the eccentric 37. This eccentric turns continuously when the machine is in operation. The turning of the eccentric causes the horizontal arm 36 to rock back and forth on the pin 34 which constitutes the pivot. This rocking back and forth or oscillation of the horizontal arm causes the blank 61 to be ground to the proper convexity or concavity, depending on whether the lap 15 or the lap 14 (Fig. 1) is used. The former, being of concave formation, produces the convex surface of either a spherical or cylindrical lens. The latter, being of convex form, produces the concave surface of either a spherical or cylindrical lens. Were it not for the oscillation of the horizontal arm 36, the spindle 59 and arbor 6 would rotate together on one axis and no relative movement between the blank 61 and the grinding lap would occur.

It would not do to have the lens spindle 59 rigidly fixed so that the lens could not revolve, and cause only the grinding arbor 6 and tool to turn as this would produce waves and streaks on the lens surface. When a lens is being ground while the lens spindle 59 occupies a neutral position (as when the lever 84 is moved to engage the notch 91 with the pin 93, Fig. 1) the lens 61 and spindle 59 revolve by friction or contact with the lap on the grinding arbor, and not through power applied to the spindle in the usual way. With the driver gear 51 out of mesh, the upright column 20 and its carried parts could be moved in either direction from its vertical position, without revolving the spindle 59 on its own axis, provided that the operator were careful not to grasp the handle 80. With the brake 87 applied, the operator may use the handle 80 in moving the column without danger of revolving the spindle 59, thus throwing the lower pins and slots out of alinement.

This alinement is all important in grinding either the concave or convex surface of a cylindrical lens to a predetermined axial meridian. In grinding either the convex or concave surface of a cylindrical lens, the oscillation may be stopped, but the spindle and lap should continue to revolve, which fact is not true in grinding a spherical lens. In the art of lens grinding, the grinding tools 14 and 15 are ordinarily either convex or concave, but the curvature of their surface is not necessarily of spherical form.

It may be in cylindrical form, that is, one in which the axial meridians vary.

It is a function of the machine to cause the oscillation of the horizontal arm 36 so that the lens spindle 59 swings in relation to the driving arbor 6. The clamping device 42 is useful in adjusting the lens spindle 59 into perpendicularity with the curvature of any lap, whether it be concave, convex, spherical or cylindrical, thereby causing the lens to at all times travel in a straight line across the lap in a plane at right angles to the main drive shaft 12. Various degrees of oscillation of the arm 36 are produced by lengthening or shortening the telescopic connections 38 and 39 between the arm and the eccentric which oscillates it.

Variations of pressure of the blank 61 on the grinding tool or lap are produced by adjusting the bolt 70. Such adjustments will move the presser foot 69 up or down to accordingly vary the tension of the spring 67. Although the spindle 59 is positively driven, it is, nevertheless, capable of longitudinal movement by virtue of the key and slot connections 76 and 77.

A universal or ball and socket joint is produced by the peculiar formation of the end of the spindle 63 and the lens body 60. The former has an arrangement of crossed pins 64 and 65 which occupy slots 66 in the socket 62. This arrangement permits the application of uniform and even pressure of the blank upon the grinding tool. The pressure may be applied and released while the machine is in operation. In Fig. 1, the pressure is applied. In Fig. 6, it is released.

The oscillation of the horizontal arm 36 is entirely independent of the position of the column 20. This column is radially adjustable in respect to the main drive shaft 12, the axis of which is the center on which the column is adapted to swing. The column includes a disk 19 which is mounted to turn on the end of the bushing 16 in which the shaft has bearing. The disks 19 and 18, (the latter being a part of the base 1) form part of the column adjusting means.

By unloosening the clamping device 24, (Fig. 1) the column 20 may be swung to either side or into position on the vertical center of the machine. The handle 81 is used in doing this. When the desired angular position is attained, the clamping device is tightened so that the column remains where it is put. The spindle 59 may be brought to rest by disengaging the clutch gear 51. This is done by lifting the lever 84 (Fig. 7) and moving it over until the notch 91 may be fitted down over the pin 92.

At this time the brake 87 will engage one side of the bevel gear 52 and thereby lock all driven parts depending thereon for motion. The spindle 59, too, will be locked and the subsequent grinding function will be accom-

plished by the particular lap then in position on the arbor 6 moving against the blank 61. The clutch 51 should be disengaged, or engaged, while the machine is at rest. As stated before, the bearing 79 not only aids in stabilizing the sleeve 75, but also materially rigidifies the spindle 59.

While the construction and arrangement of the improved optical lens grinding apparatus as herein described and claimed, is that of a generally preferred form, obviously modifications and changes may be made without departing from the spirit of the invention or the scope of the claims.

I claim:—

1. A device of the character described comprising an arbor, a drive shaft having means for rotating the arbor, a spindle disposed in opposition to the axis of the arbor, a train of gears for rotating the spindle from the main drive shaft, means by which one of the gears can be moved into disengagement to stop the rotation of the spindle, and means adapted to interlock with such adjacent one of the gears as will hold the spindle rigid.

2. A device of the character described comprising a base, a wall of the base having a disk, a bushing fixed in the wall and projecting from the disk, a column having a corresponding disk fitted on the projecting part of the bushing to turn thereon, clamping means engaging the disks by which the column may be adjusted at radial positions upon the bushing, a drive shaft journaled in said bushing and extending into the base, an arbor mounted in the base and projecting therefrom, means by which the arbor is rotated from the drive shaft, a shaft mounted in the column, a spindle driven by said shaft, a driving gear carried by the drive shaft, and a pinion carried by the column shaft in mesh with said gear traveling thereon when said adjustments of the column are made.

3. The combination in a device of the character described comprising an arm, a spindle carried by the arm adapted to carry an object to be ground, a sleeve on the spindle rotatable on the arm, a key in the sleeve occupying a groove in the spindle permitting a sliding movement therein, a washer on one end of the spindle, a spring on that end of the spindle below the sleeve bearing on the washer at one end, a presser foot adjacent to the end of the sleeve bearing on the spring, a bolt by which said presser foot is carried including a handle, and a sleeve carried by the opposite end of the arm in which the bolt is movable said sleeve having a slot with laterals in which the handle is to be fitted to hold various adjustments of the presser foot and corresponding tensions of the spring.

4. A device of the character described

- comprising a rotatable arbor, a rotatable spindle disposed in opposition to the axis of the arbor, an arm carrying the spindle, a support by which the arm is hingedly mounted upon said carrying means for lateral rocking motion and adjustments, means to fix the support at any one of various angular positions in a vertical plane, means to continuously rock the arm upon said support in a direction parallel to said plane while the support is in any of said positions and thereby continuously oscillate the spindle in respect to the arbor while the device is in operation, said rocking means including telescopic members, and being provided with means by which said members are tightened to rock said arm, or loosened to leave the arm unaffected while the rocking means continues to function.
- 20 5. A device of the character described comprising an arbor, means to rotate the arbor, a spindle disposed in opposition to the axis of the arbor, means to rotate the spindle including driver and driven gears, and means for disconnecting said driver gear and at the same time gripping the teeth of the driven gear to positively lock said driven gear so that the spindle is held stationary while the arbor continues to rotate.
- 30 6. A device of the character described comprising an arbor, a spindle disposed in opposition to the axis of the arbor, an arm by which the spindle is carried, a support, means by which the arm is mounted on the support to rock, means in connection with the arm to continuously rock it on its support and continuously oscillate the spindle in respect to the arbor while the device is in operation, a main drive shaft having means for rotating the arbor, driving connections for rotating the spindle during said oscillation occupying said supporting means and arm and composed of an arbor train of gears and a spindle train of gears, means incorporated in said driving connections including a gear connecting said trains, and means for shifting said gear to disconnect the trains, and stop the spindle rotation during oscillation at the same time grip the nearest gear of the spindle train to lock that train and the spindle without regard to the particular position.
- 40 7. A device of the character described comprising an arbor, a drive shaft having means for rotating the arbor, a spindle disposed in opposition to the arbor, means including a train of gears for rotating the spindle from the main drive shaft, means including a movable sleeve having such connection with one of the gears as will permit moving said gear into disengagement to thereby stop the rotation of the spindle, and means having such connection with the sleeve as to move therewith and interlock with such adjacent one of the gears as will hold said spindle rigid.
- 50 8. A device of the character described comprising an arbor, a drive shaft having means for rotating the arbor, a spindle disposed in opposition to the arbor, means including a train of gears for rotating the spindle from the main drive shaft, means including a sleeve having connection with one of the gears, means upon which the sleeve is movable, means constituting a brake with which the sleeve also has connection, and means for moving the sleeve in one direction thereby shifting said connected gear into a disengaging position and at the same time engage the brake with such adjacent one of the gears as will hold the spindle rigid.
- 60 9. A device of the character described comprising a drive shaft, a spindle, means including a train of gears for rotating the spindle from the main drive shaft, means including a sleeve having connection with one of the gears, relatively open means including a rod upon which the sleeve is movable, means including a brake with which the sleeve also has connection, relatively fixed means by which the brake is guided, and means including a lever by which the sleeve is movable in one direction upon the rod to simultaneously disengage said connected gear and engage said brake with such adjacent one of the gears as will hold the spindle rigid, said brake then being guided by said guide means.
- 70 10. A device of the character described comprising a drive shaft, a spindle, a train of gears for rotating the spindle from the main drive shaft, a pin upon which one of the driving gears is journaled, a rod fixed adjacent to the pin, means slidable on the rod having connection with said driving gears, a collar slidable on the pin and having a brake, means with which a portion of the brake has engagement for guidance independently of the pin in sliding, a lever having connection with said slidable means on the rod, said slidable means having connection with said collar, and pin and slot connections associated with said lever for holding the driving gear either in a driving, neutral or disengaged position, said brake engaging an adjacent one of the gears when the driving gear is fully disengaged to thereby hold the spindle rigid.
- 80 11. In a device of the character described, an upright column having extensions, a horizontal arm having ears overlapping the extensions, a tool spindle mounted upon the arm, a horizontal shaft journaled in the arm, an upright drive shaft journaled in the column including an extension journaled in a portion of the arm, a pin by which the arm is rockably connected with the column at said ears and extensions, gears carried by said

horizontal, extension and upright shafts, a gear slidably mounted upon the pin, and means permitting shifting said slidable gear for connection and disconnection of the 5 driving power to said spindle.

12. In a device of the character described, a column having extensions, an arm having ears overlapping the extensions, a tool spindle rotatably carried by the arm, driving means for the spindle including a plurality of shafts and gears mounted both upon the column and the arm, one of the driving gears being located at the connection between said arm and column, a pin by 10 which said connection is made through the ears and extensions, said pin providing the bearing for said driving gear, a collar also mounted on the pin and having a brake and a fork, said fork being guided upon an adjacent part of the arm, a rod fixed between 15 20

the extension of the column, and means including a sleeve slidable upon the rod having connection with both the driving gear and the collar to slide both simultaneously in respect to an adjacent one of the gears. 25

13. A device of the character described comprising a base, an upright column carried by the base, means for both supporting the column upon the base and permitting angular adjustments of the column in a vertical plane, a horizontal arm carried by the column, means by which the arm is pivoted upon the column to rock in the same direction in which the column is adjustable, an arbor journaled upon the base, a tool spindle 30 35 journaled upon the arm, means for rocking the arm upon its pivotal mounting, and common driving means for the arbor, spindle and rocking means.

HERMAN ARVENE GEORGE.
